UNITED STATES PATENT OFFICE

ERNEST HOPE, OF LEICESTER, ENGLAND, ASSIGNOR TO UNITED SHOE MACHINERY CORPORATION, OF PATERSON, NEW JERSEY, A CORPORATION OF NEW JERSEY

FINISHING TOOL

Application filed March 31, 1930, Serial No. 440,366, and in Great Britain April 12, 1929.

This invention relates to finishing tools and is herein illustrated as embodied in a finishing tool of the general type disclosed in my application for United States Letters Patent Serial No. 357,561, filed April 23, 5 1929.

Tools of the type under consideration may advantageously be employed for the buffing, polishing or other finishing treatment of 10 relatively small areas having curved or irregular shapes, as, for example, in the scouring of the curved breast surfaces of Louis heels. The tool disclosed in the application above mentioned and the tool illustrated 15 herein have certain features in common; namely, each consists of a disk of yieldable material such as rubber and is adapted to carry on its periphery a finishing cover in the form of a band of abrasive material, the 20 disk being subject to expansion by centrifugal force when rotated and thereby tending to exert an outward pressure to grip the abrasive band. In the tools disclosed in both this and the above-mentioned applica- 25 tion the disk is so supported that it can yield both radially and laterally; but inasmuch as this feature is claimed in the above-mentioned application it will not be claimed herein.

30 An object of this invention is to provide an improved finishing tool of relatively cheap and simple construction.

In accordance with this object, one feature of the invention resides in the provision of a disk of yieldable material of dished form, the disk being intended to carry upon its periphery a finishing cover and to grip the finishing cover as the disk tends to increase its diameter under the centrifugal 40 effect of rotation. As in the illustrated construction, the disk is composed of material which is normally flat, and is maintained in a dished condition by the employment of means designed to that end. It is believed 45 that the tendency, above referred to, of the disk to increase its diameter upon rotation is greater for a disk composed of normally flat material distorted into a dished form than it would be for a disk molded in dished 50 form. The same means for maintaining the

disk in its dished condition may advantageously be employed to secure the disk upon a shaft, and consists, in the illustrated machine, of a collar mounted on the shaft and having a centrally recessed face, and of means for clamping the disk against the recessed face of the collar with the central portion of the disk forced into the central recess of the collar. By locating the above-mentioned disk-securing means close to one 55 end of the shaft, interference by the shaft or by the securing means with the work as the latter is manipulated in various positions of presentation to the finishing cover 60 may be avoided.

In accordance with another feature of the invention, the disk is formed with a laterally rounded periphery, and the finishing cover, consisting of a band of abrasive material, is narrower than the thickness of the 70 disk and is molded to have a lateral curvature of a radius less than the radius of lateral curvature of the periphery of the disk. An advantage of this construction is that the edges of the abrasive cover tend to 75 become embedded in the material of the disk and are thus prevented from scratching the work.

These and other features of the invention including certain details of construction and 80 combinations of parts will be described in combination with an illustrative tool and pointed out in the claims.

Referring now to the accompanying drawing, 85

Fig. 1 is a side view, partly in section, of a tool and a finishing cover embodying the invention.

The tool illustrated in Fig. 1 comprises a soft rubber disk or bed 1 some four and a 90 half inches in diameter and about three-eighths of an inch thick. The edge of the disk is rounded to a radius of about three-sixteenths of an inch. The disk is pressed by a nut 2 and washer 3 against an end face 95 of a collar 4 about two inches in diameter which collar is clamped by the nut and washer (and through the disk) against a shoulder 5 on a spindle 6 on which these parts are mounted and the end of which is 100

threaded to receive the nut 2. The spindle, collar, disk and nut are coaxial. The end face of the collar 4 against which the disk 1 is clamped has a cone-shaped recess 7 (coaxial with the collar) into which the centre part of the disk 1 is forced by the nut 2 and washer 3, the disk being normally flat, and is in this manner deformed or distorted to assume a dished or somewhat 10 conical shape, the centre of the outer face of the disk being then bulged and being displaced or offset from the plane of the periphery of the face by about three-quarters of an inch, and the threaded end of the spindle 15 6 and the outer face of the nut 2 then lying some one quarter of an inch to the same side of this plane as the centre of said face of the disk 1. A molded abrasive band 8 which may be similar to that described in the aforementioned specification is placed on the periphery of the disk. The abrasive band is preferably, however, not quite so wide as the disk is thick and is molded so that the radius of the lateral curvature of the inside 25 face of the band is slightly less than the radius of the edge of the disk. The disk 1 in its normal condition is too large to fit the band 8. The deforming of the disk in the manner above described diminishes the 30 diameter of the periphery of the disk, and the abrasive band 8 is of such a diameter that, when the disk is clamped against the recessed face of the collar and thereby distorted as aforesaid, it can just be threaded 35 readily on the disk. When the spindle is rapidly rotated, say at 3000 R. P. M., the rapidly rotating disk 1 under centrifugal action tends to flatten itself and increase its diameter, thereby gripping the abrasive 40 band 8 firmly, and if the abrasive band is of the second form above described its edge will be slightly bedded into the disk and thus prevented from scratching or marking the work in an undesired manner. In the 45 preferred form of tool the band is of such a diameter that the disk does not, when rapidly rotated, ever quite flatten out but always remains somewhat dished. The depth of the depression at one side of the 50 disk 1 caused by the dishing, the flexibility of the disk, the speed and the diameter of the band 8 are preferably such that the end of the spindle 6 and the nut 2 do not, even when the tool is rotating, project beyond the 55 plane of the periphery of the outer face of the disk appreciably, if at all, this arrangement being advantageous in allowing sharply curved portions of work-pieces to be presented to the tool and manipulated without 60 any part of them coming into contact with the side of the disk itself or the nut or spindle.

Having described my invention, what I claim as new and desire to secure by Letters 65 Patent of the United States is:—

1. A finishing tool comprising a disk of yieldable material adapted to carry upon its periphery a finishing cover, said disk being of dished form whereby upon rotation it will tend, because of centrifugal action, to increase its diameter and thereby to grip the finishing cover. 70

2. A finishing tool comprising a disk of normally flat yieldable material adapted to carry upon its periphery a finishing cover, 75 and means for maintaining said disk in a dished condition whereby upon rotation said disk will tend, because of centrifugal action, to assume its normal form and to increase its diameter, thereby gripping the finishing 80 cover.

3. A finishing tool comprising a disk of yieldable material adapted to carry upon its periphery a finishing cover, and means for securing said disk axially upon a shaft, said 85 securing means being constructed and arranged to effect a relative axial displacement between the central and the peripheral portions of said disk to diminish the diameter of the periphery of said disk, said disk tending upon rotation to expand centrifugally to grip the finishing cover. 90

4. In combination, a disk of yieldable material, a band of finishing material adapted to be carried upon the periphery of said disk, said disk in its normal condition being too large to fit said band, and means for deforming said disk to diminish the diameter of the periphery of said disk to enable said band to be mounted upon the periphery of said disk. 100

5. In combination, a disk of yieldable material, a band of abrasive material adapted to be carried upon the periphery of said disk, said disk in its normal condition being too large to fit said band, and means for securing said disk axially upon a shaft, said securing means being constructed and arranged to effect a relative axial displacement between the central and the peripheral portions of said disk to diminish the diameter of the periphery of said disk to enable said band to be mounted upon the periphery of said disk, and said disk tending upon rotation to resume its normal condition and thereby to exert outward pressure upon said band of abrasive material. 105 110 115

6. In combination, a disk of yieldable material adapted to carry upon its periphery an abrasive cover, a shaft, a collar mounted upon said shaft and having a centrally recessed face, and means for clamping said disk against the recessed face of said collar with the central portion of the disk forced into the central recess of the collar, thereby deforming the disk to diminish the diameter of its periphery, the disk tending upon rotation to expand centrifugally to grip said band of abrasive material. 120 125

7. In combination, a disk of yieldable

material adapted to carry upon its periphery a finishing cover, a shaft having a free end, and means for securing said disk upon said shaft with the peripheral portion of the disk displaced relatively to the central portion in an outward and axial direction with respect to the shaft a distance sufficient to bring the plane of the periphery of the outer face of the disk beyond the free end of said shaft and beyond said securing means, thereby avoiding interference by the shaft or by the securing means with a work-piece to be treated.

8. In combination, a rubber disk adapted to carry upon its periphery an abrasive cover, a shaft having a free end, a collar mounted upon said shaft adjacent to the free end of said shaft, the outer face of said collar being centrally recessed, and means for clamping said rubber disk against the outer face of said collar with the central portion of the disk forced into the central recess of the collar and with the plane of the periphery of the outer face of the disk extending beyond the free end of the shaft and beyond said clamping means, thereby avoiding interference by the shaft or by the securing means with a work-piece in various positions of presentation to said abrasive cover.

9. In combination, a disk having a laterally rounded peripheral portion of yieldable material, an abrasive band narrower than the thickness of said disk mounted upon the periphery of said disk, said abrasive band being molded to have a lateral curvature of a radius less than the radius of the lateral curvature of the periphery of said disk, said disk being constructed and arranged to expand when in use to cause the edges of said abrasive band to tend to become embedded in the material of said disk.

In testimony whereof I have signed my name to this specification.

ERNEST HOPE.
